CLAIM

The ornamental design for an audio player, as shown and described.

DESCRIPTION

FIG. 1 is a front, right side, perspective view of an audio player showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged view of the speaker.

The dash-dash broken lines depict portions of the audio player that form no part of the claimed design. The dot-dash broken line showing in FIGS. 2 and 8 is for the purpose of illustrating a partially enlarged view of region "1" of FIG. 2 and forms no part of the claimed design.
